UNITED STATES PATENT OFFICE.

WILLIAM A. PENDRY, OF DETROIT, MICHIGAN.

PUPPET-VALVE.

SPECIFICATION forming part of Letters Patent No. 299,006, dated May 20, 1884.

Application filed November 19, 1883. (No model.)

To all whom it may concern:

Be it known that I, WILLIAM A. PENDRY, of Detroit, in the county of Wayne and State of Michigan, have invented a new and useful 5 Improvement in Puppet-Valves, of which the following is a specification.

The drawing is a vertical section through the steam-dome and valve, showing my invention as applied to the dry-pipe of a locomotive.

My invention consists in a modification of the valve for which Patent No. 282,766 was granted to me on the 7th of August, 1883, as hereinafter pointed out in the claims.

15 A represents the shell of the valve, made in such form as to be adapted for use as the throttle-valve of a locomotive. It will be readily understood that the shell must be made similar to that of an ordinary globe-valve 20 when it is designed for use outside of a steam-space.

B represents the valve-seat, and C represents the valve, which is made long enough to extend through the valve-seat nearly to the 25 opposite wall of the shell, the center portion being contracted and the ends enlarged, as shown.

L represents fair-leaders to guide the valve. The extended end of the valve is preferably 30 made to fit loosely in a recess, M, in the shell; but this is not absolutely essential.

D represents a rod projecting upward from valve C, carrying on its upper end a nut, F.

J represents a small valve which closes a 35 steam-passage, N, in shell A, leading from the steam-space surrounding the valve-shell to a point opposite the extended end of valve C, so that steam which passes through passage N will press against the extended end of valve C.

40 I represents a rod projecting upward from valve J, carrying on its end a nut, K.

G represents a rod answering the purpose of a valve-stem, moving in guides H on shell A, and operated by the throttle-lever through 45 a bell-crank in the usual manner. To the upper end of rod G is attached an arm, E, in which are holes through which pass the rods D I. The nuts F K are so set that when rod G is forced upward, raising arm E, nut K will 50 strike the top of arm E and raise valve J from its seat before nut F comes in contact with said arm, and consequently the main valve C

will first come to its seat when rod G is lowered.

O represents a steam-dome in which the 55 valve is placed.

The operation of my invention is as follows: When the engineer desires to open the throttle-valve, he forces rod G upward. This raises the small auxiliary valve J, and permits a current of steam to flow from the steam-dome through passage N and impinge against the extended end of the main valve C, thus balancing said valve, so that when the continued motion of rod G brings arm E against nut F 60 said valve will open easily. By changing the proportional end areas of the main valve C it may be balanced to any desired extent, as will be obvious to any mechanic. When rod G is lowered, the main valve C comes to its seat 65 while passage N is still open and a current of steam passing therethrough. This causes said main valve to close noiselessly without any shock.

If designed for use as a globe-valve, the rods 75 D I should be attached to the valve-stem substantially as they are to arm E, and the shell should be made like those now in use, plus the passage N and recess M.

What I claim as my invention, and desire to 80 secure by Letters Patent, is—

1. In combination with a main valve which extends through its seat to a point near the opposite wall of the shell, a steam-passage in the shell extending from the steam side of the 85 valve to a point opposite the extended end thereof, and a small auxiliary valve adapted to close said steam-passage, both the main and auxiliary valves being so connected with a valve-stem that the auxiliary valve will open 90 before and close after the main valve, substantially as shown and described.

2. The combination of the valve-seat B, valve C, extending through its seat and terminating in the recess M in the opposite wall of 95 the shell, steam-passage N, and valve J, said valves C and J being so connected with a valve-stem that the motion thereof will open valve J before opening valve C, substantially as shown and described.

WM. A. PENDRY.
